UNITED STATES PATENT OFFICE.

ARNOLD FOX, OF NEW YORK, N. Y.

SCREW-HOLDING ATTACHMENT TO SCREW DRIVERS.

1,403,680.

Specification of Letters Patent. Patented Jan. 17, 1922.

Application filed July 5, 1921. Serial No. 482,624.

To all whom it may concern:

Be it known that I, ARNOLD FOX, a citizen of the United States, residing at New York, in the county of Queens and State of New York, have invented a new and useful Screw-Holding Attachment to Screw Drivers, of which the following is a specification.

My invention consists of a piece of springy metal punched out of a sheet and bent so as 10 to hold a screw on the end of a screw driver, and is intended to be used where it would be inconvenient to hold the screw with one hand while turning the screw driver with the other.

15 The accompanying drawing shows the process of manufacture.

A piece of springy metal is punched out of a sheet in the shape shown in Fig. 1. The ends are then bent as shown in Fig. 2, which

shows an edgewise view of it. The cross-bar is then bent so that the two halves face one another as shown in Fig. 3. It is then ready to slip onto a screw driver as shown in Fig. 4.

I am aware that attachments consisting of several parts are used for the same purpose.

What I claim as original in my invention is

A screw-holding attachment for a screw driver comprising an H shape sheet of metal 30 having the ends of each leg somewhat turned in to form screw-engaging and driving shank engaging fingers and the said legs standing in planes at right angles to the H bar so as to face opposite sides of the 35 driver shank.

ARNOLD FOX.
